FINGER BANDAGE

Morris Solomon, Kew Gardens, N. Y.

Application June 7, 1944, Serial No. 539,099

1 Claim. (Cl. 128—157)

1

This invention relates to bandages suitable for finger ends and other purposes and is herein disclosed in some detail as embodied in a flat bandage having a normally non-adhesive surface but adapted to have an adhesive surface exposed by stripping off a gauze.

Bandages for wrapping around the body of a finger have proved useful, but have also proved very unsatisfactory for bandaging the end of a finger, partly for the reason that they tended to bulge in awkward folds in different places, and therefore were both awkward in appearance and ineffective to make a secure seal at the joints.

According to the present invention, the foregoing and other disadvantages and objections are overcome and a bandage is provided which may be used for many purposes but which, in addition, is well adapted to form a hermetically sealed finger cot even when applied by unskilled hands.

To attain these and other ends, the bandage is shown as provided with a body adapted to be wrapped around a finger and as also including a tab or extension which extends from the center of one side of the body so that the tab may be folded lengthwise across the top of a finger and carried back along the finger. The sides of the body may be folded across the tab as it lies on the finger, and adhesive surfaces of the sides may then bind the whole into a cot.

In order to enable this folding to produce a water-tight cot and a secure seal, the bandage is shown as notched at the point where the extension springs from the body of the bandage.

Other and further objects of the invention will be obvious upon an understanding of the illustrative embodiment about to be described or will be indicated in the appended claim and various advantages not referred to herein will occur to one skilled in the art upon employment of the invention in practice.

A preferred embodiment of the invention has been chosen for purposes of illustration and description and is shown in the accompanying drawings forming a part of the specification, wherein

Fig. 1 shows one form of bandage laid out flat as usually shipped, but with parts of a protective gauze pulled back;

Fig. 2 shows the bandage with the extension bent over so as to be over a finger end;

Fig. 3 shows the bandage with one side of the body bent over and adhering to the extension; and

Fig. 4 shows the bandage as closed upon a finger.

The bandage in the form shown includes a body 10 which may consist of the textile tape usually

used in producing adhesive tape, and may be entirely covered on the face with a suitable adhesive. Where only one face is coated with adhesive, an adhesive such as is used in ordinary adhesive tape bandage is satisfactory.

In the form shown, the body 10 includes a main portion 11 which may be nearly square or rectangular and an extension 12 projecting from the center of one side 13 of the portion 11, and being broad enough to cover the breadth of a typical human finger and long enough to cover most or all of the typical first joint of a finger.

To make a convenient and attractive bandage on a finger, the side 13 slopes somewhat inwardly from the base 14 of the extension 12 to the end corner 15 of that portion 11 on each side of the extension 12.

The bandage is normally provided with a permanent facing of gauze 16 covering the adhesive 20 on the face of the extension 12 and covering the portion 11 adjacent the extension 12 and the central area of the portion 11 for the width of the extension 12 and almost, but not completely, reaching the further side 17 of the portion 11.

In addition, the bandage is normally shipped with the remainder of the area of the portion 11 protected from sticking by covering it with an easily removable protective layer, so that by stripping off the protective layer, the bandage is ready 30 for use.

In the form shown, the protective layer consists of strippable gauze in the shape of a layer 18 covering the left-hand exposed area 19 of adhesive of the portion 11 and also covering most of the lower exposed area 20 of adhesive.

In Fig. 1, the lower corner of the gauze 18 is turned up, and the layer 18 is shown as extending to the end of the extension 12, thus providing the non-adhering part over the extension 12 as a handle for pulling on the gauze 18.

The right-hand exposed area 21 of adhesive and the rest of the lower exposed area 20 is shown as covered by a separate strippable layer 22 of gauze which extends beyond the center of the bandage and up over the extension 12, providing a convenient handle for stripping this separate strip of gauze to expose the adhesive area 21.

When the gauze layers 18 and 22 have been removed, the bandage is ready to be applied to a finger as by laying the permanent gauze portion upon one side of the finger with the end of the finger about at the line 13, bending the extension 12 over the end of the finger and down the other side of the finger, then bending the left hand area 23 21 over the side of the finger so that it overlies

the extension 12 on the finger and is pressed down to adhere to it and then bending the right hand area 21 over the side of the finger and pressing it down upon the extension 12 to adhere to it.

In the form of the invention shown, it is possible to make the bandage thus put on into a hermetically sealed, attractive bandage.

For that purpose, each half of the sloping side 13, where it meets the extension 12, extends into the extension forming a curved notch 23, so that where the extension is bent over the finger as seen in Fig. 2, the extension 12 bends along a neck at the line 13 and brings the notches at least part way over the finger. As a result, the areas 12 and 21 turn sharply over the bent-down extension at the notches and overlie the projecting points 24, left by the notches and form a neat, air- and water-tight joint in the form of an almost perfect cylinder as seen in Fig. 4.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described in some detail one embodiment of the invention, what is claimed is:

A bandage adapted to be utilized to protect the end of a digit, comprising, a body portion, a tapered central tab portion extending outwardly from the body portion, side portions extending outwardly from the body portion, the edges of

said tab and side portions forming inwardly extending notches in the bandage at opposite sides of said tapered central tab portion adjacent the location where the edges of said tab and side portions normally merge with each other, an adhesive at one surface of said body and tab and side portions, a first gauze layer normally overlying a portion of said adhesive in the area of the body and tab portions and terminating at a location spaced from one edge of said body portion to thereby provide adjacent said edge a narrow adhesive area free of said first gauze layer, and additional gauze layers overlying said adhesive in the areas of said side portions and in said narrow area with inner adjacent edges thereof overlapping each other and overlying said first mentioned gauze layer.
